TYPE INSERTING MECHANISM FOR
PRINTING MACHINESMorris J. Hoffman, Chicago, Ill., assignor to
International Business Machines Corporation,
New York, N. Y., a corporation of New York

Application September 21, 1933, Serial No. 690,311

16 Claims. (Cl. 276—4)

This invention relates to type inserting mechanism for printing machines and its principal object is to provide mechanism for storing a multiplicity of type bars, any one or any pair of which may be readily brought into operative position for use in connection with the printing machine and projected from the inserting mechanism into the printing machine in printing position to print information upon a card or other sheet.

As illustrated, the invention has been designed for use in connection with coupon ticket printing machines, an example of which is clearly shown and described in my pending application, Serial No. 657,531, filed February 20, 1933 for improvements in Coupon ticket printing mechanism, but it is to be understood that the invention is not limited to such use as it is applicable to many other types of printing machines in which it is frequently necessary to substitute lines of type for those in use for printing other data. Usually coupon ticket printing machines are employed for printing data upon two parallel rows of coupons that are detachable from the main body of the coupon ticket such as is used for keeping record of several workmen's labor upon a lot of articles, the data printed upon each coupon ordinarily comprising the quantity or number of pieces and identification number for the job lot and the price to be paid each workman for his particular work upon the articles represented by the coupon ticket. I have found it desirable to print this data in two rows, and I provide type bars which contain type to print the price upon each coupon at the same time that the other data is printed thereon, and inasmuch as it is frequently necessary to alter the prices, many type bars are provided in connection with each machine, which type bars ordinarily are stored in a convenient place and when a change has to be made, the type bars in the machine must be removed therefrom and replaced by the selected type bars.

In accordance with the present invention, all of the type bars that accompany the machine are stored in the inserting mechanism and the latter is located adjacent the printing machine in such position that any selected type bar or any selected pair or group of type bars may be readily moved into operative position and projected into the printing machine in position to print the data (contained on the type bars) in a line adjacent to the data printed by the type members regularly contained in the printing machine.

Another object of the present invention is to provide a carrier for the type bars having a plurality of guideways in which are contained type bars, any selected one or any selected pair or group of which may be brought into operative position and projected into the printing machine in printing position therein.

Another object is to provide bar projecting means engageable with selected type bars that have been brought into operative position, whereby said type bars may be projected into the printing machine for use therein, and retracted therefrom when it is necessary to replace them with other type bars.

The invention further consists in the several novel features of construction, arrangement and combination of parts hereinafter fully set forth and described.

The invention is clearly illustrated in the drawings accompanying this specification in which

Fig. 1 is an end elevation, partly broken out, of type inserting mechanism for printing machines, embodying a simple form of the present invention showing the same in connection with a printing machine;

Fig. 2 is an end elevation of a portion of the printing machine;

Fig. 3 is a vertical longitudinal section taken on the line 3—3 of Fig. 1, parts of the mechanism being broken away;

Fig. 4 is a fragmental perspective view of one of the type bars employed;

Fig. 5 is a fragmental perspective view of one of the guideways in which the type bars are supported;

Fig. 6 is a detail cross-section through one of the guideways and type bars taken on the line 6—6 of Fig. 3;

Fig. 7 is a detail cross-section of the guideway and type bar taken on the line 7—7 of Fig. 3 and

Fig. 8 is a detail, enlarged, sectional view of one of the bar projecting fingers and associated parts.

Referring to said drawings, which are merely schematic and illustrate one embodiment of the invention, the reference character 10 designates a printing machine which may be of any desirable character for printing data upon a card or other sheet. For convenience in illustrating the invention, I have chosen a coupon ticket printing machine constructed in accordance with the disclosure of my above identified application, to which reference may be made for a full explanation of the construction and operation of that machine. Briefly the printing machine contains

55

a pair of spaced guideways 11 adapted to receive and support a pair of type bars 12 in printing position. In the coupon ticket printing machine illustrated, the guideways 11 are provided by 5 forming notches in the upper edges of spaced plates 14 that are provided in said machine for spacing apart certain type wheels and other mechanism (not shown) and which forms no part of the present invention. The guideways 11 open 10 out through the side wall 16 of the printing machine as at 15 and the type bars are inserted through the openings 15 into the guideways 11. Suitable impression making mechanism 17 is provided in the printing machine for printing the 15 data contained on the type bars upon a coupon ticket or other card or sheet in the usual manner. The type bars 12 are positioned in the printing machine to print data adjacent other data printed by the printing elements of the printing machine. 20 In other respects, the printing machine illustrated may be constructed in accordance with the coupon ticket printing machine described and illustrated in the application above referred to, or any other suitable printing machine may be used wherein 25 it is desired to print with one or more lines of type which require occasional replacement with type bars containing different data.

The inserting mechanism is illustrated generally at 18 and is shown as mounted upon a table 30 19 which is formed at one end with a raised table 20 upon which the printing machine is definitely mounted in relation to the inserting mechanism. Uprights 21 support the table 20 at the required position above the table 19.

35 In the form of the invention illustrated, the type inserting mechanism embodies a carrier 22 here shown in the form of a drum fixedly mounted upon a shaft 23 rotatively mounted in a bearing bracket 24 at one end and a bearing member 25 at the other end. The bearing bracket 24 is supported upon the table 19 and the bearing member 25 supported upon the table 20 or upon a head 26 of the inserting mechanism. A cylindrical casing 27 surrounds the drum and 40 has the head 26 fastened to it at one end and a head 28 fastened to it at the other end. The casing, together with its heads, are stationarily mounted upon the table 19. The casing is provided for protecting the drum against injury and 45 for keeping dust and dirt away therefrom.

50 Preferably the drum is composed of disks 29, 30 rigidly mounted on the shaft 23 and a plurality of guideways 31 circumferentially disposed about the disks, extending therebetween and rigidly fastened thereto. For convenience in accurately locating the guideways 31, the disks are notched 55 at the periphery to receive the guideways and the latter are welded, soldered or otherwise fixedly secured to the disks. The guideways are preferably in the form of channels of suitable length to contain type bars of the desired length. The type bars may be as much as 18 to 24 inches 60 or more in length, and accordingly the guideways should be of a length to accommodate the longest type bars used with the printing machine.

65 At the end of the drum farthest removed from the printing machine, the guideways are provided with flanged end walls 32, and the opposite ends of the guideways are left open and provided with overhanging flanges 33. The flanged ends 32 and flanges 33 of the guideways 70 overlie the type bars and provide means for preventing them from falling out of the guideways whenever the open sides of the guideways 75 are directed downwardly. In the head 26 of the

casing are openings 34 registering with the guideways 11 of the printing machine whereby selected type bars may be projected from the drum into the guideways in the printing machine in position to print upon a coupon ticket or other card or sheet. 80

The drum may be adjusted to bring any group of two or more type bars, stored therein, into alignment with the guideways 11, and for convenience, I have illustrated a handwheel 35 upon one end of the drum shaft 23, which handwheel is provided with indicating characters that co-operate with a pointer 36 to indicate the group of type bars that are located in operative position to be inserted into the printing machine. Desirably, the handwheel 35 may be notched to permit the pointer 36 to engage therewith at definite places and thus positively hold the drum in exact position with the selected type bars held in alignment with the guideways in the printing machine. 90 95

For projecting the type bars into the guideways of the printing machine, I have provided a bar projector 37 here shown as slidably mounted upon the casing 27 and having fingers 38 engageable with the selected type bars when moved into operative position, namely the position in which they are aligned with the guideways in the printing machine. At the ends of the type bars farthest removed from the printing machine, 100 each is provided with notches 39 into which a finger 38 may be inserted so as to couple the bar projector with the selected type bars. The fingers 38 are contained in slide blocks 40 that are mounted on the casing wall and guided to move 105 along slots 41 formed therein, and the upper ends of the fingers are connected by a handle 42 provided with a knob 43 by means of which the fingers may be depressed into the notches of the type bars and whereby the latter may be slid 110 into the guideways of the printing machine and retracted therefrom. Coiled compression springs between the handle 42 and guide blocks 40 serve to retract the fingers from the notches. 115

120 The type bars shown comprise channel shaped bars provided along their length with spaced tongues 44 that overlie the channel, and the type 45 are set between the said tongues. The tongues space the groups of type apart so that when the type bar is inserted in the printing machine, the 125 several groups of type will print at the proper places on the coupon ticket or other sheet. The type are locked in the channel bar by a strip 46 which extends through notches in the type and extends underneath the tongues 44 on one side 130 of the channel bar.

135 In Fig. 1, the type bars 12 are shown only in the two guideways 31 that are in operative position in alignment with the guideways 11 in the printing machine. It is to be understood, however, that all of the guideways may be loaded with type bars. Furthermore the guideways are arranged in pairs about the circumference of the drum so that any selected pair may be brought into operation the 140 position illustrated in Fig. 1. Each pair of guideways comprise a group, but the group may consist of more than two guideways if so desired.

145 Desirably the casing 27 may be formed with a hinged section 47, locked thereto by a lock 48, and the bar projector may be mounted on this hinged section. With the hinged section, access may be had to the drum for the purpose of replacing any type bar in case this becomes necessary. To remove a type bar from the drum it is moved slightly to the right as viewed in Fig. 3 to dis- 150

engage its other end from the flange of the end wall of the guideway, whereupon the type bar may be withdrawn.

In the operation of the mechanism, the drum is loaded with the type bars, the companion bars of the pairs or groups being placed in the respective groups of guideways. Wishing to print data with a certain pair or group of type bars, the attendant turns the handwheel until the identifying number thereon, corresponding with the selected group of type bars, appears at the pointer and the latter slips into the adjacent notch in the handwheel. The selected type bars now have been adjusted into alignment with the group of guideways in the printing machine. The attendant thereupon depresses the handle of the bar projector thereby engaging the fingers thereof in the notches of the selected type bars, and pushes the bar projector toward the printing machine until the type bars are stopped in the machine, in which position the type on said type bars are located in proper position to print on the coupon ticket or other sheet in the printing machine. The impression or impressions are then made as usual. It will be noted that the type bars remain partly in the guideways in the drum thereby locking the drum against movement. Wishing to print with other type bars, the bar projector is re-engaged with the type bars in use, and moved back, thereby retracting them from the printing machine, whereupon another group can be moved to operative position as before.

It is to be understood that the term "type bar" is understood to include the several kinds of printing elements such as interchangeable set type locked in a holder, plates, slugs and so forth, now commonly in use.

I claim as new and desire to secure by Letters Patent:

1. In mechanism of the character described, the combination of a carrier having a plurality of guideways therein, means for moving the carrier to bring any selected guideway into operative position, and type bars slidably supported in said guideways, and each containing spaced groups of type therein, said bars, with the type therein, being adapted to be projected from the guideway when in operative position.

2. In mechanism of the character described, the combination of a drum having circumferentially disposed guideways therein, type bars slidably supported in said guideways, each type bar having spaced groups of type therein, means for rotating the drum to bring any selected type bar into operative position, and bar projecting means engageable with the selected type bar at said operative position.

3. In mechanism of the character described, the combination of a drum having circumferentially disposed groups of guideways therein, means for rotating the drum to bring any selected group of guideways into operative position, and type bars slidably supported in said guideways, the type bars contained in the group of guideways, located at the operative position thereof, being capable of being projected from said pair of guideways.

4. In mechanism of the character described, the combination of a carrier having a plurality of pairs of guideways therein, type bars slidably supported in said guideways, means for moving the carrier to bring any selected pair of type bars into operative position and bar projecting means engageable with said selected pair of bars at their operative position.

5. In mechanism of the character described, the combination of a drum having circumferentially disposed pairs of guideways, type bars slidably mounted in said guideways, setting means for moving said drum to bring any selected pair of type bars into operative position, and bar projecting means engageable with said selected pair of type bars at their operative position. 80

6. In mechanism of the character described, the combination of a rotatable drum having circumferentially disposed groups of guideways therein, and capable of being rotated whereby to bring any selected group of guideways into operative position, type bars slidably guided in said guideways, and slidably guided bar projecting means 85 having bar engaging elements adapted to engage the type bars located at their operative position.

7. In mechanism of the character described, the combination of a rotatable drum having circumferentially disposed groups of guideways therein, 90 and capable of being rotated to bring any selected group of guideways into operative position, type bars slidably guided in said guideways, a bar projecting means engageable with the group of type bars located in said operative position, and guiding means for guiding said bar projecting means to move in parallel relation to said type bar guideways. 95

8. In mechanism of the character described, the combination with a printing machine having a 100 guideway therein for receiving and holding a type bar in printing position, of a carrier mounted adjacent thereto and having a plurality of guideways, any selected one of which is adapted to be moved into alignment with the guideway in the 105 printing machine, and type bars slidably supported in the guideways of the carrier, any one of which is adapted to be projected into the guideway in the printing machine, when its associated guideway is aligned with the guideway in the 110 printing machine. 115

9. In mechanism of the character described, the combination with a printing machine having a 120 group of guideways therein for receiving and holding a group of type bars in printing position, of a drum mounted adjacent the printing machine and having a plurality of groups of guideways, circumferentially disposed about the drum, setting means for bringing any selected group of guideways of the drum into alignment with the 125 group of guideways in the printing machine, and type bars slidably mounted in the guideways of the drum, and adapted, when in operative position, to be projected into the group of guideways in the printing machine. 130

10. In mechanism of the character described, the combination with a printing machine having a 135 group of guideways therein for receiving and holding a group of type bars in printing position, of a drum mounted adjacent the printing machine and having a plurality of groups of guideways, circumferentially disposed about the drum, setting means for bringing any selected group of guideways of the drum into alignment with the 140 group of guideways in the printing machine, type bars slidably mounted in the guideways of the drum, and adapted, when in operative position, to be projected into the group of guideways in the 145 printing machine, and bar projecting means engageable with the group of type bars contained in the guideways of the drum aligned with the guideways of the printing machine.

11. In mechanism of the character described, the combination with a printing machine having a 150 group of guideways therein for receiving and

holding a group of type bars in printing position, of a drum mounted adjacent the printing machine and having a plurality of groups of guideways, circumferentially disposed about the drum, setting means for bringing any selected group of guideways of the drum into alignment with the group of guideways in the printing machine, type bars slidably mounted in the guideways of the drum, and adapted, when in operative position, to be projected into the group of guideways in the printing machine, bar projecting means engageable with the group of type bars contained in the guideways of the drum aligned with the guideways of the printing machine; and guide means for said bar projecting means extending parallel with said type bars.

12. In mechanism of the character described, the combination of a printing machine having a group of guideways therein for receiving and holding a group of type bars in printing position, of a drum rotatively mounted adjacent said machine and having a plurality of groups of guideways circumferentially disposed about the drum, the latter being capable of being rotated to bring any selected group of guideways thereof into alignment with the group of guideways in the printing machine, and type bars slidably supported in said guideways in the drum, any selected group of which is insertable into the guideways in the machine when the group of guideways containing the selected group of type bars are aligned with the guideways in the machine.

13. In mechanism of the character described, the combination of a drum having guideways, disposed above its circumference, type bars slidably guided in said guideways, a casing enclosing the drum, a shaft upon which the drum is

mounted, a handwheel on said shaft for rotating the same, bar projecting means external of the casing and having means engageable with selected type bars, whereby to project said selected type bars from the guideways.

14. The combination with a table, of a printing machine mounted thereon and having a group of guideways for receiving and holding type bars in printing position, and type bar storing mechanism mounted on said table and having type bar selecting mechanism and type bar inserting means arranged to insert selected type bars into the guideways in the printing machine.

15. Storing and inserting mechanism for printing machines of the character having guideways for receiving and holding type bars in printing position, said mechanism comprising a carrier having guideways for slidably holding a plurality of type bars, and capable of being adjusted to bring any selected type bars into alignment with the guideways in the printing machine.

16. In mechanism of the character described, the combination with a coupon ticket printing machine having a pair of guideways therein for receiving and holding a pair of type bars in printing position, of a drum like carrier mounted adjacent thereto and having a plurality of pairs of guideways, any selected pair of which is adapted to be moved into alignment with the guideways in the coupon ticket printing machine, and type bars slidably supported in the guideways of the carrier, any pair of which is adapted to be projected into the guideways in the coupon ticket printing machine, when its associated guideways are aligned with the guideways in the coupon ticket printing machine.
